Inventor
F. Henderson,

By *Oliver O'Brien*
Attorney

UNITED STATES PATENT OFFICE.

FRED HENDERSON, OF BISBEE, ARIZONA.

ELEVATOR SUPPORT.

Application filed October 15, 1927. Serial No. 226,417.

The present invention relates to improvements in elevator supports, and has reference more particularly to an improvement over Patent No. 1,622,943 of March 29, 1927.

5 One of the important objects of the present invention is to provide a means for holding the cage at a floor level while it is being loaded or unloaded, the means being capable of adjustment, which was one of the disadvantages of the supporting means disclosed in the aforementioned patent.

10 A further object is to provide an elevator support which is simple in construction, inexpensive, strong, and durable and further well adapted to the purpose for which it is designed.

15 Other objects and advantages of the invention will become apparent from the following description taken in connection with the 20 accompanying drawing.

In the accompanying drawing forming part of this application and in which like numerals indicate corresponding parts throughout the several views:

25 Figure 1 is a fragmentary side elevation of an elevator or cage showing the manner in which the same is held at a floor level by my improved support.

Figure 2 is a view taken at right angles to 30 Figure 1.

In the drawing wherein for the purpose of illustration is shown the preferred embodiment of my invention, the numeral 1 designates generally the cage or elevator, the same being adapted for vertical movement within the shaft 2 in the manner well known in the art.

Secured on one of the timbers 3 of the shaft 40 at a suitable distance above one of the floor levels is the metallic strap 4, the same being formed at its lower end with an eye 5. My improved elevator support further includes the provision of an elongated rod 6 which is formed at its upper end with an eye for interfitting engagement with the eye 5 and the lower end of this elongated rod 6 is welded or otherwise secured to a turn buckle 7. An elongated eye bolt 8 has its upper threaded end threaded into the other end of the turn 45 buckle 7 and a lock nut 9 is arranged on the threaded portion of the bolt for engagement

with the lower end of the turn buckle for holding the eye bolt in any predetermined adjusted position.

A link 10 is carried by the eye portion 11 55 formed on the lower end of this eye bolt 8 and this link is freely swingable.

A hook member 12 has its inner end portion secured to the lower portion of the cage or elevator 1 and the outer free end of this hook 60 extends beyond the side of the cage. When the cage reaches a floor level, it is simply necessary to swing the interconnected rod and eye bolt outwardly and place the link 10 in engagement with the hook 12 in the manner 65 as clearly shown in the drawing. This will hold the cage at the floor level so that it can be unloaded or loaded without any danger of the elevator moving. However, when the cage or elevator starts upward, the hook 12 70 will automatically become disengaged from the link 10 and the interconnected rod and eye bolt will swing out of the path of movement of the cage. It will therefore be unnecessary to manually disengage the hook 75 from the links.

While I have shown the support as being associated on one side of the shaft, it is to be understood that a similar support may be also employed on the other side of the shaft, and a 80 complementary hook carried by the adjacent side of the cage.

It has been found in using the elevator support disclosed in Patent No. 1,622,943 that the chain 5 forming a part of the support in 85 this patent stretched and did not permit proper adjustment. It is therefore necessary to employ an elevator support of the character embodied in the present invention in order to obtain the proper adjustment so 90 that the elevator or cage may be held on a level with the floor.

While I have shown the preferred embodiment of my invention, it is to be understood that minor changes may be made therein 95 without departing from the spirit of the invention and the scope of the appended claim.

Having thus described the invention, what I claim as new is:—

In combination with a cage and its shaft, 100 a metallic strap secured on one of the timbers of the shaft, the lower end of the strap being

formed with an eye, an elongated rod having an eye formed at its upper end for interfitting engagement with the aforementioned eye, a turnbuckle secured at its upper end on the lower end of said rod, an eye bolt having its upper end threaded into the lower end of the turnbuckle, a link attached to the eye por-

tion of the eye bolt, and a hook secured on the bottom of the cage at one side thereof and extending outwardly therefrom for detachable engagement with said link. 10

In testimony whereof I affix my signature.

FRED HENDERSON.
